Inventor.

Lee P. Hynes,

By his Attorney

E. H. Bentley

UNITED STATES PATENT OFFICE.

LEE P. HYNES, OF ALBANY, NEW YORK, ASSIGNOR TO CONSOLIDATED CAR-HEATING COMPANY, OF ALBANY, NEW YORK, A CORPORATION OF WEST VIRGINIA.

AUTOMATIC REVERSER FOR DOOR ENGINES.

Application filed March 22, 1922. Serial No. 545,916.

To all whom it may concern:

Be it known that I, LEE P. HYNES, a citizen of the United States, residing at Albany, in the county of Albany and State 5 of New York, have invented certain new and useful Improvements in Automatic Reversers for Door Engines, the following being a full, clear, and exact disclosure of the one form of my invention which I at 10 present deem preferable.

For a detailed description of the present form of my invention, reference may be had to the following specification and to the accompanying drawing, wherein

15 Fig. 1 shows a door and its operating engine, here indicated as of the pneumatic type with a torsion switch in the door-operating shaft;

20 Fig. 2 is a diagram of the electric circuits. My present invention is designed to eliminate the usual door-shoe now commonly employed on engine-driven doors to reverse the engine in the event of its meeting an obstruction. Such a door-shoe is mounted 25 on the front edge of the door and yields when it strikes the obstruction and thereby acts electrically to stop or to reverse the engine.

20 In place of such a door-shoe, I introduce in the driving means between the door and engine a yielding connection which, in the event of the door meeting an obstruction, will operate an electric emergency switch that will cause the reversal of the engine. 35 When the pressure on the engine is released the yielding connection will resume its normal position and again start the engine on its door-closing movement. This yielding connection and switch I term, for convenience, a torsion switch, since I prefer to locate it in a shaft which drives the radial door-operating arm, but the title is not intended to limit its essential character. To make such a device workable, I have contrived certain associated features which will 45 be described hereinafter.

Referring to the drawing, A represents a door, which is shown, for convenience, as a sliding door of any suitable kind, such, for 50 instance, as is now commonly used on railway cars. This door is operated by means of a radial arm D on a shaft B². In the

outer end of arm D is a roller that travels up and down in a vertical guide d on the rear edge of the door. The door is moved 55 from one end to the other of its course by a movement of approximately 180 degrees rotation of the arm D and shaft B². In line with shaft B² is a supplementary shaft B¹ which is driven in a well known manner 60 by an air engine B conventionally illustrated. On the respective shafts B¹ and B² are the arms A¹ and A², which are shown in greater detail in Fig. 2. These arms A¹ and A² are normally held together by a 65 spring F, which will not yield under normal circumstances, but are so adjusted and arranged that in the closing movement of the door, an obstruction of the door will cause 70 the two arms to separate under the stress 75 of the rotary shaft B¹ as it endeavors to move the door. On arm A¹ is a small switchboard a¹, carrying four contacts 6, 7, 8 and 9. On arm A² is a switch-blade a² which normally bridges contacts 6 and 7, 80 but in the aforesaid emergency will be drawn away from those contacts, breaking the circuit connection between them, and bridge the opposite set of contacts 8 and 9.

In Fig. 2 is a hand-switch K which, for 80 door-closing, will be turned to the position C, shown in full lines, and for door opening will be turned to the opposite position O shown in dotted lines. In the full-line position, C, it will bridge contacts 4 85 and 5 and will bridge contacts 2 and 3 in its dotted-line position, O. In this figure the door A will, at the end of its closing run, open limit switch 10 and at the end of its opening run will open limit-switch 11, these 90 limit-switches being closed at all other times. C¹ and O¹ represent magnets which, in a well known manner, control the engine valves to give it a door-opening or a door-closing movement respectively. Illustrations of magnetic control of this type may 95 be found in Letters Patent 1,247,653 to Farmer and 1,287,717 to McElroy.

Assuming the door to be open, limit-switch 10 being then closed and limit-switch 11 open, the movement of switch K to its full-line or closing position, C, will give a circuit from battery R to limit-switch 10, which is now closed, to contacts 4 and 5, of

the hand-switch, to contacts 6 and 7 of the torsion-switch, to door-closing magnet C¹. The door will then proceed to close, but if it encounters an obstruction, the torsion-switch will be shifted, as heretofore explained, to open contacts 6 and 7 and then close contacts 8 and 9. That will de-energize magnet C¹ and establish a new circuit from battery R, to limit-switch 10, contacts 8 and 9 to door-opening magnet O¹. Thereupon the door will reverse its direction of travel and continue its opening movement until the pressure on the torsion-switch is relieved and that switch shifted to break the door-opening circuit at 8 and 9, closing the circuit of door-closing magnet C¹ at 6 and 7. The door will again reverse and resume its door-closing progress until it finally opens limit-switch 10, thereby breaking the door-closing circuit of magnet C¹ and leaving it broken, as shown in Fig. 2. When the door is to be opened again hand-switch K is turned to its opening position, O, closing contacts 2 and 3. That establishes a circuit from battery R, to limit-switch 11, which is now closed, to contacts 2, 3 and door-opening magnet O¹. The door will then proceed to open until it finally breaks the circuit of magnet O¹ at the limit-switch 11. By this arrangement a satisfactory control of the door is provided without resort to the door-shoe which has several objectionable features.

What I claim as new and desire to secure by Letters Patent is:—

1. The combination with a door-engine, of a yielding connection between it and the door, a magnetic controller for the engine, a hand-switch therefor, and a switch operated by said yielding connection for automatically reversing the effect of said controller.

2. The combination with a door-engine, of a yielding connection between it and the door, opening and closing magnets for controlling said engine, a hand-switch for said magnets, and a switch operated by the said yielding connection for shifting the control of the engine from one to the other of said magnets.

3. The combination with a door-engine, of a yielding connection between it and the door, a magnetic controller for the engine, a hand-switch therefor, limit-switches operated by the door and acting on said controller, and a switch operated by said yielding connection for reversing automatically the effect of said controller.

4. The combination with a door-engine, of a yielding connection between it and the door, an opening and a closing magnet for controlling the engine, a hand-switch for said magnets, a switch operated by the said yielding connection for reversing the effect of said magnets, and limit-switches between

said hand-switch and the source of current operated by the respective movements of the door.

5. The combination with a door-engine, of a torsion-switch in the engine shaft, a magnetic controller for the engine, a hand-switch therefor, and connecting wires between said controller and the source of current including the contacts of said torsion-switch.

6. The combination with a door-engine, of a yielding connection between it and the door, two magnets controlling respectively the opening and closing movements of the engine, a hand-switch containing contacts in each of the respective circuits of said magnets, and a switch operated by said yielding connection containing normally-closed contacts in the circuit of the door-closing magnet and normally-open contacts in the circuit of the door-opening magnet.

7. The combination with a door-engine, of a yielding connection between it and the door, an emergency switch controlled by said connection, a controller for the engine including two magnets, one for opening and one for closing the door, a hand-switch, a circuit for the door-closing magnet containing contacts on the hand-switch and normally-closed contacts on the emergency switch, and two circuits for the door-opening magnet, one containing contacts on the hand-switch, the other containing normally-open contacts on the emergency switch.

8. The combination with a door-engine having a rotary shaft in two parts, a spring holding the two parts in alignment, an emergency switch operating on the divergence of said parts, from alignment, a magnetic controller for the engine, a hand-switch for said controller, limit-switches for said controller operated by the respective movements of the door, and circuits controlled by said emergency switch for automatically reversing the effect of said controller.

9. The combination with a pneumatic door-engine, of a yielding connection between it and the door, a magnetic controller for the engine, a hand-switch for said controller, and an emergency switch for said controller having normally-set contacts and operated by the yielding connection to reverse the engine when the door meets an obstruction.

10. The combination with a pneumatic door-engine, of a yielding actuating connection between it and the door and a reverser for the engine controlled by said yielding connection.

11. The combination with a pneumatic door-engine, of a yielding connection between it and the door, a controller for the engine including two engine-valve-controlling magnets, a hand-switch for said controller, and an emergency switch operated

by said yielding connection and containing normally-closed contacts in the circuit of the door-closing magnet and normally-open contacts in the circuit of the door-opening magnet.

5 net.

12. The combination with a door engine, and a door controlled thereby, of a magnetic controller for the engine, a manual circuit closing device for said magnetic controller,

a yieldable member connected with the door, 10 and circuit closing means associated with said yieldable member for automatically reversing the effect of said controller.

Signed at New York city, county of New York, and State of New York, this 21st day 15 of March, 1922.

LEE P. HYNES.
